MANUFACTURE OF ARCH SUPPORTING SHOES

Simon G. Ross and Charles T. Anderson, Cincinnati, Ohio, assignors to United Shoe Machinery Corporation, Paterson, N. J., a corporation of New Jersey

Application October 24, 1933, Serial No. 694,984

3 Claims. (Cl. 12—142)

This invention relates to the manufacture of arch supporting shoes and it is particularly concerned with the problem of providing effective and lasting support for the inner longitudinal arch of the foot.

Numerous expedients have been adopted by shoe manufacturers to afford suitable support for the longitudinal or instep arch of the foot. For example, it has been customary to employ for this purpose so-called orthopedic insoles, i. e., insoles of the type in which a lateral extension or "wing" is provided on the inside shank portion of the insole, the extension being designed to overlie the inside of the shoe upper beneath the instep of the foot and usually being pressed or molded against the side of the last in the process of making the shoe so that it will conform more or less closely to the foot. Such insole extensions, however, fail to retain their original shape and position in the shoe as the latter is worn but quickly break down under the weight and pressure of the foot and so become incapable of performing their intended function.

In view of the foregoing, the present invention, in one aspect, provides an improved method of making arch supporting shoes which, as herein exemplified consists in introducing an arch supporting piece between one side of a last and a shoe upper member on the last, working the upper member over the last and thereby conforming the arch supporting piece to the side of the last, securing marginal portions of the upper member and the arch supporting piece in overlasted positions upon an insole on the last, and securing an outsole to the shoe by means of through-and-through stitches extending through the upper member, the arch supporting piece, and the insole. The illustrated arch supporting saddle is composed of a piece of colloid-treated or pyroxylin-impregnated fabric such, for example, as cotton cloth coated or impregnated with nitrocellulose. As illustrated the saddle is arranged to underlie only that portion beneath the instep at the inside shank portion of the foot. Preferably the supporting piece or saddle is softened, as by means of a suitable solvent, for example acetone, prior to the assembly of the saddle with the other parts of the shoe, and the softened saddle is inserted between the upper and the lining after the latter have been pulled over the insole and secured in pulled-over position to the heel and toe portions of the insole and last. The upper and the lining are then lasted in the usual way and secured, in overlasted relation, to the insole. Thereafter an outsole is laid and, as herein illus-

trated, the outsole is secured to the shoe by means of through-and-through stitching which serves not only to unite the outer and inner soles and the overlasted margins of the upper and the lining but also firmly to secure the saddle to the bottom of the shoe. The saddle, being in a softened, semi-plastic, condition during the side lasting operation, will be conformed to the contour of the side of the last by the pressure applied thereto by the upper as the latter is stretched and tensioned over the last. Moreover, the softened pyroxylin or nitrocellulose will penetrate the upper and the lining and, on account of its adhesive character, as the solvent dries out it will firmly secure the saddle, the upper and the lining together. When dry the parts thus united will be stiff enough to retain the shape of the surface of the last against which they have been pressed while still being sufficiently yielding and elastic to accommodate the normal movements of the bones and muscles of the foot.

Other aspects and features of the invention will be apparent from the following description and will be specifically pointed out in the claims.

The invention will now be explained with reference to the accompanying drawing, in which—

Fig. 1 is a perspective view of an apparatus such as may be advantageously employed for the purpose of softening or conditioning an arch supporting saddle prior to its assembly with the parts of a shoe;

Fig. 2 is a perspective view of an arch supporting shoe in the process of manufacture, illustrating particularly the appearance of the shoe after the upper has been pulled over the last and a softened arch supporting saddle has been introduced between the upper and the upper lining preparatory to the performance of the side lasting operation;

Fig. 3 is a fragmentary cross-sectional view of the shoe as it appears after the upper has been side lasted and its lower margin secured in overlasted relation to the insole; and

Fig. 4 is a cross-sectional view of the completed shoe.

For the purpose of providing effective support for the longitudinal arch of a foot, the shoe illustrated in Fig. 4 of the drawing is provided with an arch supporting piece 10 of sheet material which is located between the upper 12 and the upper lining 14 at the inside shank or waist portion of the shoe and which is shaped and arranged to underlie and fit the hollow portion beneath the instep at the inner side of the foot, the supporting piece being securely attached to the shoe in 55

such a manner as to constitute a support in the nature of a saddle for sustaining the instep portion of the foot. The illustrated supporting piece or saddle 10 is located forwardly of the counter 16 and its lower marginal portion, together with the adjacent marginal portions of the upper and the lining, are overlasted upon the insole 18 and are firmly attached to the insole and to the outsole 20 by means of stitches 22 which extend 10 through both soles and through the upper, the lining, and the saddle. As shown, the saddle 10 is died out or otherwise cut to substantially the shape shown in Fig. 2, having an upper edge 24 which is curved to facilitate insertion of the 15 piece between the upper and the lining and to adapt the piece to fit within the hollow inside instep portion of the foot, and a curved lower edge 26 so shaped as to insure that the lower marginal portion of the supporting piece which is lasted 20 over the insole shall be of substantially uniform width to correspond to the substantially uniform width of the adjacent overlasted portions of the upper and the lining. Preferably, the supporting piece is made of material which is normally of 25 sufficient stiffness to provide adequate support for the arch of the foot but which is capable of being softened to facilitate the shaping or molding of the piece to the contour of the last in the process of making the shoe, and which when softened will 30 be of such a character as will serve adhesively to secure the supporting piece to the upper materials of the shoe as well as to impregnate and stiffen the adjacent portions of the upper materials. It has been found satisfactory to employ 35 for this purpose a colloid-treated fabric such, for example, as cotton cloth impregnated or coated with nitrocellulose as disclosed in United States Letters Patent No. 1,256,240, granted February 12, 1918, on an application of Stanley P. Lovell.

40 In making a shoe embodying the arch supporting features of the present invention, as exemplified in the drawing, the insole 18 is first secured in place upon the bottom of a last 30 and the upper 12 having the lining 14 assembled therewith is 45 placed upon the last, pulled over and secured at the toe and heel portions in the usual manner as by means of tacks 28. The supporting piece or saddle 10 having been first softened is introduced between the upper 12 and the lining 14 at the 50 inside shank portion of the shoe, as indicated in Fig. 2. In case a doubler is employed the supporting piece may advantageously be introduced between the lining and the doubler. If, in accordance with the preferred practice, the sup- 55 porting piece 10 is made of colloid-treated fabric, a suitable softening of the adhesive stiffening material may be effected by dipping the supporting piece in acetone or by subjecting it to the action of a machine such as the conditioning machine 60 disclosed in United States Letters Patent No. 1,895,524, granted January 31, 1933, upon application of A. R. Schoenky. A portion of a conditioning machine, such as just referred to, is shown at 32 in Fig. 1. This figure also shows a 65 supporting piece or saddle 10 which has been operated upon by the machine and which rests upon a delivery table 34 ready to be removed by the operator who is to assemble it with the upper materials of the shoe.

70 After the supporting piece or saddle 10 has been assembled with the pulled-over upper materials the latter are worked over the last by means of such a machine, for example, as the side lasting machine disclosed in United States Letters Patent No. 1,815,296, granted July 21, 1931, upon ap-

plication of George Goddu. As a result of the side lasting operation as performed by that machine, the upper materials are stretched tightly over the sides of the last and the margins of the upper materials, together with the margin of the supporting piece, are wiped inwardly over the insole 18 and firmly secured in overwiped position on the insole by means of staples, one of which is shown at 36 in Fig. 3. On account of the softened condition of the supporting piece or saddle 10 the side lasting operation results also in conforming or molding the saddle to the exact shape of the last. As the solvent in the supporting piece and in the adjacent impregnated portions of the upper and the lining dries or evaporates the nitrocellulose or other stiffening medium hardens or stiffens and thus a laminated arch supporting structure is provided in which the several plies or laminations are securely cemented together and are of such stiffness as to retain the shape of the last imparted to them during the working and tensioning of the upper materials in the side lasting operation. In this way the supporting piece or saddle and the attached portions of the upper materials of the shoe are thus shaped or molded to the contour of the particular last upon which the shoe is made although they are capable of yielding as may be required when the shoe is worn to accommodate the normal movements of the bones and muscles as the foot flexes in walk- 30 ing.

After the upper has been lasted and a suitable filler has been applied, as indicated at 38 in Fig. 4, to the space between the overlasted upper margins, an outsole 20 is laid and secured in place on the shoe as by means of cement in a well-known manner. The shoe is then removed from the last and the outsole attached by means of through-and-through stitching, such as that indicated at 22 in Fig. 4, the stitching extending 40 through the outsole and the insole and through the overlasted marginal portions of the upper materials including the counter 16. As shown, the stitching 22 at the inside shank portion of the shoe extends also through the overlasted 45 margin of the supporting piece or saddle 10, thus securely and permanently attaching the saddle to the bottom of the shoe by the same through-and-through stitching which secures together the insole, the outsole and the upper materials. The 50 saddle being secured to both the upper and the lining at the side of the shoe by means of the nitrocellulose or other adhesive stiffening material with which it is impregnated, and being firmly held in place at the bottom of the shoe 55 by the through-and-through stitching which also secures the outsole to the shoe, and also by means of the staples 36, the saddle will have no tendency to break down and become displaced under the strains to which it is subjected while the shoe 60 is being worn but will retain its proper shape and location and continue efficiently to perform its arch supporting function throughout the life of the shoe.

While the saddle is herein shown as being 65 located entirely in front of the counter it has in some instances been found desirable to arrange the saddle with its rear portion overlapping the outer side of the forward extremity of the counter, the saddle serving, in such cases, to hold the forward portion of the counter in position to afford additional support for the arch of the foot. It is considered undesirable, however, to have the counter overlie any substantial portion of the saddle since such an arrangement would tend to 70 75

interfere with the requisite molding of the saddle to the shape of the last in the operation of side lasting the upper. If desired, however, the saddle may be formed as an integral forward extension of a premolded counter in which case the extending saddle portion only of the counter may be softened prior to its assembly with the upper and thereafter molded to the shape of the last in the performance of the side lasting 10 operation.

The invention is not necessarily restricted to the provision of an arch supporting element at the inside shank portion only of a shoe since it is contemplated that an arch supporting member 15 or saddle may be employed, if desired, at both sides of the shoe thereby producing what may be termed a "corset" type of shoe. Moreover, the arch supporting member or members may be assembled with the upper without having been 20 previously softened. It may, for example, be found desirable to assemble an unsoftened saddle piece with the upper materials when the latter are assembled in the stitching room, the saddle piece being conveniently secured in place by 25 means of the stitching which unites the vamp and the quarter. Later, after the upper has been pulled over, but before it has been side lasted, the saddle may be softened by solvent applied thereto by means of a brush.

30 While herein exemplified in its application to the manufacture of shoes having outsoles attached by through-and-through stitching, it is to be understood that the invention is not restricted thereto since, in various aspects, it is 35 applicable also to shoes of other types such, for example, as welt shoes or shoes in which the outsole is attached by means of cement.

Having described our invention, what we claim as new and desire to secure by Letters Patent of the United States is:

40 1. That improvement in methods of making arch supporting shoes which consists in introducing an arch supporting piece between one side of a last and a shoe upper member on the last, working the upper member over the last and

thereby conforming the arch supporting piece to the side of the last, securing marginal portions of said upper member and said arch supporting piece in overlasted positions upon an insole on the last, and securing an outsole to the shoe by 5 means of through-and-through stitches extending through said upper member and said supporting piece and said insole.

2. That improvement in methods of making arch supporting shoes which consists in assembling 10 an arch supporting piece between outer and inner members of a shoe upper on a last, conforming the upper and the arch supporting piece to the contour of the last, adhesively securing the arch supporting piece to both members of the 15 upper at the side of the last, securing marginal portions of said upper members and said supporting piece in overlasted positions upon an insole on the last, laying an outsole, and permanently securing the outsole to the shoe by stitching 20 extending through the outsole and through said upper members, said supporting piece, and said insole.

3. That improvement in methods of making arch supporting shoes which consists in assembling 25 an insole, an upper, an upper lining, and a counter upon a last, pulling over the upper and the lining and securing them to the insole, softening a pyroxylin-impregnated saddle by a solvent and inserting the saddle between the upper and 30 the lining in a location forward of the counter, working the upper and lining over the last thereby shaping the saddle to the last, securing the upper, the lining and the saddle in overlasted position upon the insole, allowing the shoe to 35 remain upon the last until the pyroxylin has hardened thereby securing the saddle to the upper and the lining and causing the saddle to retain the shape of the last, laying an outsole, pulling the last, and securing together the insole, 40 the outsole, and the overlasted margins of the upper, lining, counter and saddle by means of a line of through-and-through stitching.

SIMON G. ROSS.
CHARLES T. ANDERSON.
